UNITED STATES PATENT OFFICE.

HORACE E. MARTIN, OF ATHENS, GEORGIA.

CHAIN SAW.

1,107,625.

Specification of Letters Patent. Patented Aug. 18, 1914.

Application filed August 7, 1913. Serial No. 783,688.

To all whom it may concern:

Be it known that I, HORACE E. MARTIN, a citizen of the United States, residing at Athens, in the county of Clarke and State of Georgia, have invented certain new and useful Improvements in Chain Saws; and I do hereby declare the following to be a full, clear, and exact description of the invention, such as will enable others skilled in the art to which it appertains to make and use the same.

This invention relates to chain saws and more particularly to those specially adapted to cut down growing trees; and it consists in the novel construction and combination of the parts hereinafter fully described and claimed.

In the drawings, Figure 1 is a side view of a portion of a chain saw constructed according to this invention. Fig. 2 is a similar side view with one row of side links and cutting teeth removed, and showing in dotted lines the outline of the beveled portions which form the teeth of the other row of side links. Fig. 3 is a plan view of a portion of the chain saw. Fig. 4 is a cross-section, taken on the line $x-x$ in Fig. 1.

The chain saw is formed of an endless chain of pivoted links provided with teeth, and it is adapted to run on a supporting frame of any approved construction, and to be driven by any approved driving mechanism.

Three kinds of side links 2, 3 and 4 are provided and are arranged opposite to each other in pairs. One pair of side links 2 is arranged alternately of each two pairs of side links 3 and 4, and the side links 2 are connecting and supporting links only, and are not provided with cutting teeth. The side teeth 3 and 4 are provided with cutting teeth 5, and these teeth are made in various shapes in carrying out this invention. The cutting teeth are preferably made of the shape shown, being curved forwardly and projecting over the front ends of the links to which they pertain for about one-half the length of the links.

The front end portions of the shanks of the cutting teeth of the links 3 rest against the upper rear end portions of the connecting links 2, and the front end portions of the shanks of the cutting teeth of the links 4 rest against the rear end portions of the shanks of the cutting teeth of the links 3. The shanks of the cutting teeth of the links

3 and 4 differ somewhat in shape, but the cutting portions of the teeth 5 are preferably alike.

Each side link has an inclined projection 6 at its rear end, which overlaps an inclined projection 7 on the front end of the next adjacent link, and prevents the saw from bending in one direction.

Three kinds of center links 8, 9 and 10 are provided, and are arranged alternately in regular order. The center links 8 are provided with forwardly projecting drag teeth or planer teeth 12, the side portions 14 of which are wider than the links 8 so that they form stops which rest on the tops of the connecting side links 2. The drag tooth links 8 are pivoted to the rear end portions of the side links 4 and to the front end portions of the connecting side links 2 by pivot pins 15. The drag teeth are hook-shaped, and have rearwardly and upwardly inclined shanks 16.

The center links 9 are provided with gage teeth 17, and are pivoted by pins 18 to the rear end portions of the connecting side links 2 and to the front end portions of the side links 3. The gage teeth project over each end of the links 9 and are arranged to extend between the top portions of the adjacent pairs of cutting teeth 5. The front end portions 19 of the shanks of the gage teeth are curved and they overlap the drag teeth and their shanks.

The center links 10 are pivoted by pins 20 to the rear end portions of the side links 3 and to the front end portions of the side links 4. The center links 10 have upwardly projecting lugs 21 which form abutments for the rear end portions of the gage teeth 17 and their shanks.

All the center links have downwardly projecting lugs 22, or other approved means, for engaging with the driving wheel or wheels by which the saw is operated. The overlapping portion of the links and the shanks of the teeth prevent the saw from bending in one direction when the saw is straight, and permit it to bend in the opposite direction so that it may pass over and engage with the supporting and driving wheels. These overlapping portions also strengthen or stiffen the teeth and prevent vibrations, and enable the saw to be used to advantage as a cross-cut saw for green lumber. As the drag teeth have laterally projecting side portions they plane out the

whole of the wood which has been sliced by the cutting teeth. The gage teeth prevent the cutting and drag teeth from cutting too deeply at a single cut, and the saw is therefore relieved from too much strain.

What I claim is:

1. In a chain saw, the combination, with side links arranged in pairs in sets of three, each two adjacent pairs of side links being provided with cutting teeth, and the remaining pair being connecting links; of three series of center links arranged in line with each other and pivoted to the side links, one series of center links being provided with drag teeth, the second series having gage teeth, and the third series being connecting links.

2. In a chain saw, the combination, with side links arranged in pairs in sets of three, two adjacent pairs of the side links being provided with forwardly and upwardly curved cutting teeth which project longitudinally beyond the ends of the links to which they pertain, and the remaining pair being connecting links; of three series of center links arranged in line with each other and pivoted to the side links, one series of center links being provided with drag teeth, the second series having gage teeth, and the third series being connecting links.

3. In a chain saw, the combination, with side links certain of which are provided with forwardly projecting cutting teeth arranged opposite to each other in pairs, of center links pivoted to the side links, certain of the center links being provided with drag teeth having laterally projecting portions for the projecting front end portions of the cutting teeth to overlap and rest on.

4. In a chain saw, the combination, with side links certain of which are provided with cutting teeth, of center links pivoted to the side links, certain of the center links being provided with drag teeth having laterally projecting side portions which rest

on the connecting side links between the toothed side links.

5. In a chain saw, the combination, with side links provided with cutting teeth arranged opposite to each other in pairs, of center links pivoted to the side links, certain of the center links being provided with gage teeth which extend longitudinally between the cutting portions of two adjacent pairs of cutting teeth.

6. In a chain saw, the combination, with side links provided with cutting teeth arranged opposite to each other in pairs, of center links pivoted to the side links, certain of the center links being provided with gage teeth which extend longitudinally between the cutting portions of two adjacent pairs of cutting teeth, and the center links next behind those with the gage teeth being provided with projecting abutments for the rear end of the gage teeth.

7. In a chain saw, the combination, with side links provided with cutting teeth arranged opposite to each other in pairs, of center links pivoted to the side links, certain of the center links being provided with drag teeth, and the center links next behind those with the drag teeth being provided with gage teeth having forwardly projecting end portions which overlap and reinforce the shanks of the drag teeth.

8. In a chain saw, the combination, with side links certain of which are provided with forwardly projecting cutting teeth arranged in pairs and adjacent to each other, the rear pair of teeth overlapping and resting on the shanks of the front pair, of center links pivoted to the side links.

In testimony whereof I have affixed my signature in the presence of two witnesses.

HORACE E. MARTIN.
